UNITED STATES PATENT OFFICE.

FRANKLIN W. FILLMORE, OF ATLANTIC CITY, NEW JERSEY.

DESIGN FOR A WALL-CABINET.

No. 38,308.

Specification for Design.

Patented Nov. 6, 1906.

Application filed September 10, 1906. Serial No. 334,069. Term of patent 3½ years.

To all whom it may concern.

Be it known that I, FRANKLIN W. FILLMORE, a citizen of the United States, residing at Atlantic City, New Jersey, have invented a new, original, and ornamental Design for Wall-Cabinets, of which the following is a specification, reference being had to the accompanying drawing, forming a part thereof.

The figures show a front view or elevation and an end view of my new design.

I claim—

The ornamental design for a wall-cabinet as shown.

FRANKLIN W. FILLMORE.

Witnesses:

F. L. MIDDLETON,
EDWARD N. SARTON.
